UNITED STATES PATENT OFFICE

2,663,420

DISCHARGE DEVICE FOR CAN ASSORTING MACHINES

George J. Palmer, Long Beach, Calif.

Application February 28, 1949, Serial No. 78,813

8 Claims. (Cl. 209—74)

1

My invention relates to the field of canning machinery, and more particularly to a device adapted to automatically separate non-labeled and defectively labeled cylindrical cans or containers from a stream of perfectly labeled cans during the time the cans are in motion.

Although several defectively labeled and non-labeled can detecting and rejecting devices have been devised and marketed in the past, including the devices disclosed in my patents, No. 2,560,737 and No. 2,590,343, the majority of these devices have the disadvantage that they employ a gate mechanism for rejecting purposes. Due to this structure the gate must open and close to permit each non-labeled or defectively labeled can to fall therethrough, with the result that the volume of the cans being discharged into the device from a labeler cannot exceed a certain maximum speed. Should the maximum volume be exceeded, the gate is unable to complete an opening and closing cycle between the time the first defectively labeled or non-labeled can and a second such can passes therover, with the result that the second can is not rejected.

The primary purpose of my present invention is to provide a can handling device that will eliminate the disadvantages of the presently available non-labeled and defectively labeled rejecting devices, and one that will operate satisfactorily irrespective of the volume of cans passing therethrough.

A major object of my invention is to provide a can handling device adapted to be positioned between a labeler and conveyor system, with the device when so positioned being capable of separating defectively labeled and non-labeled cans from a stream of cans rolling therethrough irrespective of the speed with which the cans are traveling so long as it is relatively constant.

Another object of my invention is to furnish a can handling device that occupies a minimum of floor space, requires a minimum of maintenance attention, has a relatively simple mechanical structure, and can be adjusted to handle cylindrical cans and containers of varied size.

These and other objects and advantages of my invention will become apparent from the following description of a preferred form thereof, and from the drawings illustrating that form in which:

Fig. 1 is a side elevational view of my can handling device;

Fig. 2 is a plan view of the can ejecting mechanism used in the device;

Fig. 3 is a side elevational view of the solenoid

2

controlled mechanism used in releasing one of the spring loaded pins which engages a defectively labeled or non-labeled can;

Fig. 4 is an enlarged vertical cross-sectional view of the solenoid controlled pin releasing mechanism taken on the line 4—4 of Fig. 3;

Fig. 5 is an enlarged vertical cross-sectional view taken on the line 5—5 of Fig. 1 of the pin retracting mechanism used in disengaging a pair of the pins from one of the non-labeled or defectively labeled cans;

Fig. 6 is an enlarged vertical cross-sectional view of one of the disk supported pins in a non-engaging position taken on the line 6—6 of Fig. 1.

Referring now to Figs. 1 and 2 for the general arrangement of my invention, it will be seen that it includes a downwardly extending track T, over which cylindrical cans or containers C roll from a conventional labeler L to a conveyor system

S. Immediately positioned above the track T are two laterally spaced, power-driven disks D, with each disk having a number of spring loaded pins P annularly disposed and situated near the periphery thereof. Each two oppositely disposed pins P when actuated are adapted to move inwardly and grasp the ends of a non-labeled or defectively labeled can C and move the can upwardly as the disks D rotate.

After the non-labeled or defectively labeled cans C have been raised to a predetermined horizontal plane, the pins P are retracted and permit the can C held therebetween to be deposited on a set of downwardly inclined rails R over which the can rolls to a suitable area where it is held separately from the perfectly labeled cans. The non-labeled cans may be immediately removed from this area and returned through the labeler, with the defectively labeled cans being similarly handled after the defective labels have been removed therefrom. The means used in detecting non-labeled and defectively labeled cans passing along the track T may be any one of the means disclosed in my patents No. 2,560,737 and No. 2,590,343, or such other detecting means as desired.

In Figs. 1, 2 and 4 it will be seen that the track T includes two laterally spaced, longitudinally extending rails 10. Each rail 10 is formed from a strip of rigid material 11 of rectangular cross section along the upper surface of which the rims of the cans C rotate, with the rail having a flange 12 extending along the outer side thereof to serve as a guide for the cans C. It will be apparent that the rails forming the track T can be formed

50 as an integral unit, or fabricated from a strip 11

and flange 12 as previously described. Each of the track rails 10 is supported in the desired position by being affixed to the upper portion of a number of vertically positioned members 13, with each of the members having a recessed portion formed on the lower portion thereof. The recessed portion of each of the members 13 engages the upper and inner portions of a longitudinally extending side piece 14 of rectangular cross-section, which side piece extends substantially the distance between the labeler L and the conveyor system S.

Each side piece 14 is supported near the ends thereof on a horizontally positioned member 15 having an I-shaped cross-section. The member 15 includes a horizontal web 16, a vertical flange 17 at one end thereof, another vertical flange 18 at the other end thereof, and a rib 19 formed on the upper surface of the web 16 and extending inwardly a substantial distance from the inner face of the flange 18. Each of the side pieces 14 is held in position on the members 15 by bolts 20 which extend through the flanges 17 and 18 to engage the side pieces. One of the side pieces 14 is adapted to have the downwardly positioned surface thereof rest on the upper edges of the ribs 19. When shims are placed between the inner flange 18 and the outer face of side piece 14 the side piece may be transversely adjusted to vary the width between the track rails 10 to adjust for can size. By such an arrangement my can handling device may be utilized in removing non-labeled and mis-labeled cans from a stream of cylindrical containers ranging in size from the flat cans such as employed for packing fish up to the relatively large cans in which fruit juices are marketed.

To maintain the members 15 in the desired vertical position each member is provided with a leg 22 on each side thereof, with the legs being bolted or otherwise affixed to the lower portion of the flanges 17 and 18. Although any rigid material may be used I have found it desirable to fabricate the legs 22 from strap steel which is bent into the desired shape. Reinforcement of the legs is provided by a horizontally positioned rigid pipe 23 extending between each two adjoining legs 22 securely positioned therebetween by a bolt 23a which serves to reinforce the legs and hold them in a rigid position by having the bolt 23a which passes through the lower portion of legs 22 engage the upper portion of a cast iron shoe 24 provided on each leg. Each shoe 24 is provided with a rectangular base 25 which has a vertically extending slot 25a formed in the outer portion thereof whereby the shoe may be held in the desired position on a floor when the slot is engaged by a bolt imbedded therein. To further reinforce the legs 22 two rigid members 27 are provided which extend longitudinally between the legs in a conventional manner.

In Fig. 1 it will be seen that with the track T supported on the above described framework, it can be disposed between the labeler L and conveyor S in such a manner that the cans C will be discharged from the labeler onto the track and proceed in rolling motion to the conveyor. The defectively labeled or non-labeled cans C rolling along the track T are segregated from the perfectly labeled cans by being lifted upwardly therefrom and deposited on the rails R by the disks D as hereinafter described.

The disks D are positioned above the track T, and laterally spaced from one another, each disk including an annular plate 29 which has a hub

30 formed on the exterior face thereof. A horizontally positioned shaft 31 passes through each hub 30, with each hub being rigidly affixed to the shaft in the desired location by a set screw (not shown) of conventional design. The ends of the shaft 31 are rotatably supported in pillow blocks 32, which have two longitudinally spaced vertical bores formed therein through which the threaded portions of two vertically positioned rods 33 pass upwardly therethrough. A pair of nuts 33a is provided for and engages the threaded portion of each of the rods 33 to hold the blocks 32 in position thereon.

Each rod 33 engages the bores formed in two vertically aligned ears 35, with each set of ears being formed on and extending outwardly from one end of a rectangular member 36 of channel shaped cross-section that is slidably mounted on one of the side pieces 14. The ears 35 each have a set screw 37 threaded into a tapped bore formed therein whereby the rods 33 can be adjusted to the desired vertical height. Each of the members 36 is also provided with a set screw (not shown) whereby the members may be slidably adjusted along the side pieces 14, and held in the desired position by adjusting the set screws.

Situated on a bracket 38 of conventional design extending between the rods 33 is an electric motor 39 adapted to drive a gear reducing unit 40, also mounted on the bracket by means of a belt 41. The gear reducer 40 is provided on one side with a sprocket which engages an endless chain belt 43 that on its upper end engages a sprocket 44 rigidly mounted on one end of the shaft 31. Thus, when the motor 39 is placed in operation, the sprocket 44 is rotated, and the shaft supported disks D rotated at a speed approximating the velocity of the can C rolling along the track T as will hereinafter be explained.

In Figs. 1 and 2 it will be noted that each of the disks D is provided near the periphery thereof with a series of tapped bores that are engaged by bolts 45 having tubular spacers 46 situated thereon. An annular ring 47 having a series of bores formed therein is supported from each disk D between the outer ends of the spacers 46 and the inner faces of the heads provided on the bolts 45. Each of the pins P is slidably mounted in one of the bores 49 formed in the plate 29, and a similarly positioned bore 59 formed in the ring 47. The pins P each include a shank portion 51 on which an annular collar 52 is integrally formed, and an annular flange 53 is formed on the outer portion of each collar 52. A helical spring 54 encircling the outer portion of each shank 51 is provided, with each spring being disposed between the inner face of the ring 47 and the outer face of one of the flanges 53, whereby the inner ends of the pins P at all times are forced inwardly into a can engaging position.

A number of tapped bores 55 are formed in the plate 29 which are inwardly toward hub 29 and situated directly below a pin-supporting bore 49. A bolt 56 threadedly engages each of the bores 55, with the bolt having a conventional washer 57 positioned adjacent to the head portion thereof and a tubular member 58 supported thereon situated adjacent to the plate 29. Each of the tubular members 58 (Figs. 4 and 5) has an annular flange 59 formed on the outer end thereof for reasons which will hereinafter be explained. The bolts 56 each have a key 60 pivotally mounted thereon, each of which is adapted to retract one of the pins P from a can-engaging position after

the can C has been raised to the desired horizontal plane.

In Fig. 6 it will be seen that each of the pins P is normally held in a non-can-engaging position by a substantially rectangular pin actuating member 61. The member 61 has an annular bore 62 formed in the outer portion thereof that is of greater diameter than the collar 52 and permits it to move transversely therethrough. The inner portion of the member 61 has a longitudinally extending slot 63 formed therein which slidably engages the member 53 and permits limited inner and outer movement of the actuating member 61. A clip spring 61a situated in such a manner as to engage the inner ends of one of the members 61, tends at all times to force member 61 upwardly. The spring 61a is preferably supported from a screw 64 and disposed below and between two of the bolts 56, with the screw engaging a tapped bore formed in the plate 20.

In Fig. 6 it will be seen that the inner end of each pin P is prevented from moving inwardly to a can-engaging position as the outer face of the collar 52 engages a portion of the inner face of the member 61. When the pin actuating member 61 moves radially inwardly upon detection of a defectively labeled or non-labeled can, the bore 62 is brought in alignment with the collar 52 which slides inwardly into the bore to permit the inner ends of the pin P to engage a defectively labeled or non-labeled can C. The inward movement of the pin P is limited when vertical face of the collar 52 contacts the outer face of one of the plates 28. When the defectively labeled or non-labeled can C is engaged by two oppositely disposed pins P, it is rotated by disks D to the desired horizontal elevation where it is deposited onto rails R (as will hereinafter be explained), with the engaging pins P at this point brought into a retracted and non-can-engaging position as seen in Figure 5.

To retract the pins P after the defectively labeled and non-labeled cans have been raised to the desired horizontal plane, each of the disks D has a substantially horizontally positioned roller 65 positioned adjacent to the outer face thereof. Each of the rollers 65 is rotatably mounted on a bolt that is affixed to one of the pillow blocks 32, with each of the blocks thus serving as a support for the shaft 31 as well as the roller 65.

In Fig. 5 it will be seen that the pin retracting operation occurs as the inner portions of two oppositely disposed keys 69 are engaged by the rollers 65, with the inner portions of the keys being pivoted inwardly towards the plates 28 and the upper portions of the keys being pivoted outwardly to engage the flanges 53, thus moving the pins P to a non-can-engaging position. As each collar 52 is moved outwardly from within the confines of the bore 62 the clip spring 61a slidably moves the pin actuating member 61 outwardly to the position shown in Fig. 5. After the key has passed the roller 65 the helical spring 54 tends to move the pin inwardly, but the pin P cannot assume a can engaging position as the vertical face of the collar 52 engages a portion of the outer face of the pin actuating member 61. The pin P will remain in a non-can-engaging position until the pin actuating member 61 is moved inwardly to a position where the bore 62 is in alignment with the collar 52 whereupon the collar is slidably moved through the bore by compression on the helical spring 54 to place the pin in a can engaging position.

When a defectively labeled or non-labeled can

C reaches a position on the track T substantially under the shaft 31, the presence of the defectively labeled or non-labeled can is signaled by one of the detecting devices disclosed in my patents, No. 2,560,737 and No. 2,590,343. Upon the signal being received an electrically operated solenoid device E is brought into action to contact two oppositely situated pin actuating members 61, with the result that they are moved inwardly to cause two of the bores 62 and collars 52 to be brought into alignment, permitting two of the pins P to be forced inwardly and engage a non-labeled or defectively labeled can which is carried upwardly from the stream of perfectly labeled cans and deposited on the rails R.

A vertically positioned rectangular plate 68 having four longitudinally extending slots 69 formed therein is provided for each side of my device. The slots 69 are engaged by bolts or machine screws 70 that engage tapped openings formed in the vertically positioned edges of the members 36, with the result that the plates 68 can be vertically adjusted. Thus, by adjusting the bolts 70, the plates 68 can be positioned at the desired vertical elevation for reasons which will hereinafter be explained. Each of the plates 68 serves as a support for an electric solenoid 71 which is mounted thereon by a conventional bracket 72.

Each solenoid 71 has a plunger slidably mounted therein which has two vertically spaced lugs 73 affixed thereto, with the lugs supporting a vertically positioned screw 74 therebetween. A horizontally positioned screw 75 is adjustably mounted in a member 76 of conventional design that is supported from the plate 68, for controlling the horizontal throw of the solenoid controlled plunger. A shaft 77 is rotatably mounted in a bore formed in the upper portion of each of the plates 68, with the outer end of each shaft supporting a crank 78 which extends downwardly to engage the screw 74. The opposite end of the shaft 77 supports a lever 79, with the outer end of the lever moving upwardly as the crank 78 is rotated in a counterclockwise direction due to electrical energization of the solenoid 71. When the outer ends of levers 79 move upwardly and engage the pin actuating members 61, the members 61 also move upwardly sufficiently to bring the bores 62 in alignment with the collars 52. This movement of the pin actuating members 61 permits the springs 54 to force two of the pins P inwardly into a can engaging position.

It will be apparent that should the levers 79 remain in the upward position the pin actuating members 61 would be moved upwardly as the disks D rotate, with the result that the pins P controlled by them would all be placed in a can engaging position. As it is only desired to remove the defectively labeled or non-labeled cans from the stream of perfectly labeled cans passing between the disks D, the solenoids 71 are only momentarily energized which permits the solenoid controlled plungers to return to their normal position in which the levers 79 do not engage the pin actuating members 61 as can best be seen in Fig. 3. To break the electric circuit to the solenoid 71 after it has moved the lever 79 to a pin actuating location, an L-shaped member 80 is affixed to the lower portion of the screw 74. A horizontally adjustable screw 81 is supported on the lower end of member 80, one end of which is at all times in contact with a spring loaded member 82 which is used in actuating a snap switch 83. Upon the solenoids 71 being

electrically energized through two conductors 83a, the plungers (not shown) are pulled inwardly, the levers 79 placed in position to move one set of pin actuating members 61 upwardly, and the adjustment screws 81 moved rearwardly to break the circuit to the solenoids by engaging and moving the member 82 rearwardly. After the circuit to the solenoids 71 has been broken, the spring loaded member 82 moves the L-shaped members 80 and the solenoid plungers forwardly to again place the levers 79 in a position whereby they will not contact the pin actuating members 61 until a non-labeled or defectively labeled can is detected and the solenoid again electrically energized to place two of the pins P in a can engaging position.

Upon detection of a defectively labeled or non-labeled can and the solenoids 71 being electrically energized to place the pins P in a can engaging position, the can is grasped between the two pins and raised upwardly between the disks D until the pins are placed in a retracted position by the keys 60 engaging the rollers 65. When the defectively labeled or non-labeled can is released by the pins P it is positioned over the rails R which slope downwardly away from my device, and over which the defectively labeled or non-labeled cans roll to an area where they are stored or again run through the labeler.

The shaft 31 has two annular spacers 84 mounted thereon, with each of the spacers being adjacent to the interior face of one of the plates 29. Two bearings 85 are rotatably mounted on the shaft 31, each of which is situated adjacent to the interior face of one of the spacers 84. Each bearing 85 has a rail 86 extending rearwardly therefrom, on which the defectively labeled or non-labeled cans roll along. The rails 86 are held at the desired distance from one another by two connecting members 87 which are pivotally joined at their junction point by a machine screw 88. Thus, by loosening and tightening the screws 88 the width between the rails 86 can be regulated to accommodate various sized cans. A set of guides 89 of a conventional design extend longitudinally along the rails 86, and serve to prevent defectively labeled or non-labeled cans from falling or being deflected from the rails 86.

Although by experience I have found that the above described device operates very satisfactorily in removing non-labeled and defectively labeled cans from a stream of perfectly labeled cans rolling along the track T, it will be apparent that other rotating means may be used in raising the defectively labeled or non-labeled cans to the rails R.

It will be apparent that the disk mounted can engaging pins P may be placed in a can engaging position by a number of mechanisms other than the particular ones I have previously discussed in detail.

In the present application no claim is made to the defectively labeled and non-labeled can detecting means independently, which means are fully disclosed in my patents, No. 2,560,737 and No. 2,590,343. To furnish an actuating vacuum for my non-labeled and defectively labeled detecting device a vacuum pump 130 driven from a conventional motor 131 is provided, or should it be desired the motor 39 can also be used for this purpose. A conduit 132 extends to the detecting device, while another conduit 134 is connected to the discharge of the pump 130 and extended upwardly to the track T to use the dis-

charged air in blowing loose labels as disclosed in my above mentioned Patent No. 2,560,737.

An electronic circuit adapted for use with my non-labeled and defectively labeled can detecting device is shown in Fig. 8 of my Patent No. 2,560,737. In my present invention the electrical switch 83 and the switches used to break the circuit to the solenoids (shown in the alternate forms of my device) after one of the cans C has been engaged correspond generally to the switch 115 in my Patent No. 2,560,737. In the prior device the switch 115 was momentarily placed in the open position to cause de-energization of the solenoids by a can passed thereover, while in my present invention the same result is achieved by the movement of the solenoid operated plunger.

The operation of my invention is extremely simple. A stream of cans C is discharged from the labeler L to the track T, with the perfectly labeled cans rolling undisturbed between the disks D to the conveyor system S. However, a defectively labeled or non-labeled can is detected by a unit U, which letter represents any one of the detecting devices disclosed in my two previously mentioned patents or such other detecting unit as may be found desirable.

When the unit U signals the presence of a defectively labeled or non-labeled can, an electronic circuit is actuated causing two oppositely disposed pins P to be placed in a can engaging position. The defectively labeled or non-labeled can C is then carried upwardly and deposited on the rails R where it rolls to an area in which it is segregated from the perfectly labeled cans. In operating the disk form of my device it is desirable that the peripheral speed of the disks D be substantially the same as the lineal velocity of the cans C passing therebetween.

The adjustment of the disks D on the track T is made possible by longitudinally moving the blocks 36, with the elevation of the disks being regulated by raising or lowering the rods 33.

While the particular devices herein shown and described in detail are fully capable of attaining the objects and providing the advantages hereinbefore stated, it is to be understood that they are merely illustrative of the presently preferred forms of my invention, and that I do not mean to limit myself to the details of construction or design herein shown other than as defined in the appended claims.

I claim:

1. A rejecting device which includes: two laterally spaced rotatably mounted disks between which a plurality of cans may move without interruption; means for rotating said disks; a plurality of spring loaded pins slidably supported in a transverse position on each of said disks; means to hold said pins in a non-can engaging position; means to actuate two of said pins which are oppositely disposed to a can engaging position; and means to retract said two can engaging pins to a non-can engaging position after said rejected can has been raised above the horizontal plane in which it was engaged.

2. A can rejecting device which includes: two laterally spaced driven disks between which a plurality of cans may roll without interruption; a plurality of spring loaded pins slidably mounted in a transverse position on each of said disks; a plurality of radially positioned pin actuating members, with each of said members being operatively associated with one of said pins, and said members holding said pins in a non-can engaging position; means for actuating two of

said members to place two oppositely disposed pins in a can engaging position; a plurality of keys, with each of said keys being operatively associated with one of said pins, and each of said keys upon movement being applied thereto retracting one of said pins into a non-can engaging position; and means to apply pressure to two of said keys after a rejected can has been raised to a predetermined height to cause said two engaging pins to be disengaged from said can.

3. A can rejecting device which includes: two laterally spaced driven disks; two annular rings, with each of said rings rigidly supported from the exterior face of one of said disks; a plurality of transversely positioned pins, with each of said pins having a collar formed thereon, and said pins being slidably mounted in bores formed in said disks and rings; a plurality of helical springs, with each of said springs encircling one of said pins, and being situated between the inner face of one of said rings and the outer face of one of said collars; a plurality of radially movable pin actuating members, with each of said members being movably mounted on one of said disks and having a bore formed therein that engages one of said pins and prevents said pin from assuming a can engaging position until said member is moved inwardly to permit said collar to pass through said bore; a plurality of flanges, with each of said flanges being formed on the outer end of one of said collars; a plurality of keys movably mounted on each of said disks, with the outer end of each of said keys engaging one of said flanges; two levers, with each of said levers being adapted to be moved upwardly to contact and move inwardly one of said pin actuating members upon the presence of a rejected can being detected and to place said pin controlled thereby in a can engaging position; and roller means to contact said keys to retract said pins from a can engaging position after said rejected can has been raised by said pins to a predetermined height.

4. A rotatable member for a can rejecting device which includes: a rotatable disk; an annular ring rigidly mounted on said disk; a plurality of pins, with each of said pins being transversely positioned between said disk and ring and movably supported thereon; a plurality of flanged collars, with each of said collars formed on one of said pins, and situated between the outer face of said disk and the inner face of said collar; a plurality of springs, with each of said springs being situated between the inner face of said ring and the outer end of one of said collars; a plurality of pin actuating members, with each of said members having a bore formed therein through which one of said pins extends, and each of said members being radially movable on said disk; a plurality of keys pivotally supported from said disk, with the outer end of each of said keys engaging one of said flanged collars; and spring means urging said pin actuating members into a position where said pin that is controlled thereby is held in a non-can engaging position which occurs as the inner end of each of said keys is moved inwardly.

5. A pin actuating mechanism for use on a disk employed in a can rejecting device which includes: an annular plate, having a plurality of spaced bores formed therein adjacent to the periphery thereof; a ring rigidly supported from said plate, with said ring having bores formed therein that are in alignment with said bores formed in said plate; a plurality of pins, with

each of said pins slidably mounted in said bores formed in said plate and ring; a plurality of collars, with each of said collars disposed on one of said pins; a plurality of radially positioned pin actuating members, with each of said members being movably supported from said plate and operatively associated with one of said collars to hold said pin controlled thereby normally in a non-can engaging position, but said member when moved radially permitting said pin to assume a can engaging position; and means to retract each of said actuated pins to a non-can engaging position.

6. A device to reject defective cans which includes: two laterally spaced annular members between which a plurality of cans may pass without interruption; means to continuously rotate said annular members in synchronism; a plurality of circumferentially spaced movable members oppositely mounted on said annular members; spring means urging said movable members inwardly to grasp one of said cans therebetween; movable means that normally prevents actuation of said movable members; electrically operated actuating means which upon receipt of an electrical signal indicating the presence of a defective can moves said movable means to cause a portion of said movable members inwardly by said spring means to engage said defective can; means that move said can engaging members to a non-engaging position to release said defective can when said annular members reach a predetermined position; and means to maintain said movable members in a non-engaging position after said movable members release said defective can.

7. A device to reject defective cans which includes: two laterally spaced disks mounted on a driven shaft; two annular rings; means to rigidly support said rings on oppositely disposed faces of said disks in spaced relationship therewith, with each of said disks and rings having a plurality of circumferentially spaced aligned bores formed therein, and said rings sufficiently spaced from one another to permit a plurality of cans to pass therebetween; a plurality of oppositely disposed pins, the inner portion of said pins slidably supported in bores formed in said rings, and the outer portion of said pins in the oppositely disposed bores formed in said disk from which said ring is supported; a plurality of collars formed on said pins, with each of said collars disposed on one of said pins between said ring and disk; a plurality of helical springs under compression each encircling one of said pins, and disposed between the outer face of one of said collars and the inner face of one of said disks; movable means operatively associated with said collars that normally maintain said pins in a position where the opposing end portions thereof do not project inwardly beyond the opposing faces of said rings; electrically operated actuating means which upon receipt of an electrical signal indicating the presence of a defective can actuates said movable means to permit a portion of said pins to move inwardly by said spring means to engage said defective can; means that move said pins to a non-engaging position to release said defective can when said engaging pins have been rotated a predetermined distance; and means to maintain said pins in a non-engaging position after release of said defective can.

8. A device to reject defective cans which includes: two laterally spaced disks mounted on a driven shaft; two annular rings; means to rigidly

11

support said rings on oppositely disposed face of said disks in spaced relationship therewith, with each of said disks and rings having a plurality of circumferentially spaced aligned bores formed therein, and said rings sufficiently spaced from one another to permit a plurality of cans to pass therebetween; a plurality of oppositely disposed pins, the inner portion of said pins slidably supported in bores formed in said rings, and the outer portion of said pins in the oppositely disposed bores formed in said disk from which said ring is supported; spring means that at all times urge said pins inwardly into a can engaging position; movable means operatively associated with said pins that normally prevent actuation of said pins into a can engaging position; electrically operated actuating means which upon receipt of a signal indicating the presence of a defective can actuates said mov-

12

able means to permit a portion of said pins to engage said defective can; means that move said pins to a non-engaging position to release said defective can when said disks and rings rotate to a predetermined position; and means to maintain said pins in a non-engaging position after said can is released therefrom.

GEORGE J. PALMER.
